UNITED STATES PATENT OFFICE.

EDWARD H. ELLISON, OF JAMESTOWN, NEW YORK, ASSIGNOR TO JAMESTOWN CAR PARTS MANUFACTURING COMPANY, OF JAMESTOWN, NEW YORK, A CORPORATION OF NEW YORK.

RADIATOR FOR AUTOMOBILES.

1,321,813.

Specification of Letters Patent. Patented Nov. 18, 1919.

Application filed January 19, 1917. Serial No. 143,336.

To all whom it may concern:

Be it known that I, EDWARD H. ELLISON, a citizen of the United States, residing at Jamestown, in the county of Chautauqua, 5 State of New York, have invented certain new and useful Improvements in Radiators for Automobiles, of which the following is a description, reference being had to the accompanying drawing and to the figures of 10 reference marked thereon.

The invention relates to new and useful improvements in radiators for automobiles, and more particularly to the means for securing the radiator core to the frame at the 15 upper and lower water tanks.

In connection with radiators for heavy trucks, it has been customary to provide a cast iron upper and lower tank, and also cast iron side members which are joined to 20 the tank so as to form a rigid frame. The radiator core is attached to this rigid frame. It has also been customary to grind the surface of the cast iron where the core is attached thereto, and it is a well-known fact 25 that ground surfaces are not always straight and true, and furthermore it often occurs that there are slight differences in the distance between the upper and lower tanks and also slight differences in the size of one radiator core from another:

An object of the present invention is, therefore, to provide a flexible means for connecting the radiator core to the rigid frame, which flexible means readily allows 35 the radiator core to be connected to the frame even though there be slight variations in the sizes of the cores or the distance between the tanks or slight unevenness in the surface to which the core is attached.

40 A further object of the invention is to provide a connecting means for connecting a core to the rigid frame, which connecting means includes rigid devices secured to the core and a flexible member which is also 45 secured to these rigid devices and to the rigid frame.

These and other objects will in part be obvious and will in part be hereinafter more fully disclosed.

50 In the drawings, which show by way of illustration one embodiment of the invention:—

Figure 1 is a front view of a section of an

automobile radiator embodying my improvements;

Fig. 2 is a vertical sectional view there- 55 through;

Fig. 3 is an enlarged detail section through the connection at the upper end of the radiator and the tank; and

Fig. 4 is an enlarged sectional view 60 through the connection between the radiator and the tank at the lower end of the radiator.

The invention is directed to a radiator for 65 automobiles which is particularly adapted for use in connection with heavy trucks. The radiator includes a cast iron upper tank and a cast iron lower tank which are connected by cast iron sides, and when these 70 parts are bolted together they form a very rigid frame which is capable of withstand- 75 ing the vibrations that are inherent in solid tire motor trucks. A convenient and inex- 80 pensive means of preparing the surfaces of the rigid frame to which the core of the radiator is attached is by grinding parts of the surfaces on surface grinders. It is a well-known fact that surfaces ground thus are not exactly straight and true. It is also 85 well-known that there is a slight difference in the distance between the upper and lower tanks at one side of the radiator from that at the other side of the radiator, and also that the radiator cores vary in size no mat- 90 ter how carefully they may be manufac- 95 tured.

The present invention is directed particu- 100 larly to the manner of connecting the radiator core to the radiator frame. A perfo- 105 rated metal plate is attached to the lower tank, and this forms a support for the radiator core. Extending about the sides and ends of the radiator core at the lower end thereof are metal strips and also flexible strips preferably of copper or low brass. These strips are secured together and soldered to the radiator core, and the flexible strip is clamped to the rigid frame. At the upper end of the core there is a perforated plate, also metal strips extending along the sides and ends of the radiator core, and a flexible strip. These strips and the plate are riveted or otherwise secured together and are also soldered or otherwise secured to the 110 radiator core with the flexible strip extend-

ing outwardly from the sides and ends of the core. This flexible strip is clamped to the rigid frame, and thus the radiator core is securely held in place by the flexible strips 5 at the top and the bottom thereof.

Referring more in detail to the drawings:—

My invention is directed to an automobile radiator consisting of a lower tank 10 and an upper tank 2 which are preferably formed of cast iron. These tanks are bolted to cast iron side frames, one of which is indicated at 3 in the drawings. This forms a rigid frame within which a radiator core, 15 indicated more or less diagrammatically at 4, is located. Connected to the lower tank is a perforated metal plate 5, the perforations being indicated at 6. This plate extends from side to side and end to end of the 20 lower tank and is secured thereto by clamping bolts 7.

Secured to the lower end of the radiator core along the sides and ends thereof are metal strips 8, and secured to these metal strips and also to the radiator core are flexible strips 9 which are, as above noted, preferably formed of copper or low brass. The strip 9 and the strips 8 may be riveted together or soldered together, and they may 30 also be soldered to the radiator core, the essential features consisting in rigidly securing the strips together so as to form a rigid frame at the lower end of the radiator core which is connected through this flexible strip 35 with the rigid frame of the radiator.

The flexible strip, indicated at 9 in the drawings, is clamped against the upper face of the plate 5 by the clamping bolts 7. These clamping bolts pass through flanges on the 40 side frames, and also through a strap 10 which extends from one side frame to another. The flexible strips 9 are provided with openings 11 through which the bolts 7 pass. A suitable packing or gasket, indicated at 12, may be placed between the plate 5 and the flange of the lower tank. It will be understood that the radiator core rests 45 freely on the plate 5 and is secured at its bottom to the radiator frame solely through 50 these flexible strips 9.

At the upper end of the radiator core there are metal strips 13—13 which extend along the sides and ends of the radiator core, and on top of these strips are flexible strips 55 14, and on top of the strips 14 is a perforated metal plate 15. The strips 13 and 14 and the metal plate 15 are all riveted or soldered together and are also soldered or otherwise secured to the radiator core, thus 60 forming a rigid frame for the upper end of the core. The metal plate 15 and the strips 13 may be of any desired metal, but I prefer to make the flexible strips 14 of copper or low brass, as described above in connection 65 with the strips 9. The flexible strips 14 are

secured to the upper tank by bolts 16. The flexible strips 14 are provided with elongated openings 17 through which the bolts 16 pass. The flanges on the side frames are clamped against this strip and a strip 18 70 extending from one side frame to the other is also clamped against the flexible strip. A suitable packing or gasket is placed between the strips 14 and the flange of the tank to which it is attached. 75

As above noted, it is desirable to grind the surfaces of the flanges on the tanks, and these surfaces are more or less uneven, and it sometimes happens that the distance between the flanges on the tank at one side of the radiator is greater than at the other side of the radiator frame. After the edge of the tank and both ends of the side pieces have been ground and the holes drilled, the plate 5 is laid on top of the tank, the radiator core with the rigid frames, consisting of the strips 8 and 9 at the lower end thereof and the strips 13 and 14 together with the perforated plate 15 at the upper end thereof, is then set on the top of the plate 5. The cast iron side pieces are put in place, and the bolts 7 are drawn up tight, thus securing the side pieces to the lower tank and the flexible strip 9 to the lower tank. The upper tank is then placed on the side castings, 80 and said side castings if necessary sprung into place and the bolts 16 inserted in the openings in the side plates and upper tank. The core, however, is not sprung so as to cause any strain whatever on the same, but is 85 allowed to remain in its natural position, and if it tilts either toward the front or the back the oblong holes 17 in the strip permit of this tilting. The bolts 16 are then drawn tight, and this firmly clamps the upper end 90 of the radiator core. The drawing up of the bolts securing the parts of the frame in no way transmits any strain upon the radiator core even though the plate 5 may be 95 twisted or bent when the bolts are drawn tight. The soldered joints between the frames attached to the radiator core will 100 maintain their maximum strength as they cannot be broken loose at any short interval owing to the flexibility of the strips which 105 secure the radiator core to the rigid frame, but will have to break loose on a whole side 110 at once. 115

It is obvious that minor changes in the details of construction and the arrangement of parts may be made when desired without departing from the spirit of this invention as set forth in the appended claims. 120

Having thus described the invention, what is claimed as new is:—

1. In an automobile radiator, the combination of a rigid frame including upper and lower tanks and a radiator core, means forming a rigid frame at the upper and lower portions of said core, a flexible metal 125

strip secured thereto and means connecting said strip to said upper and lower tanks.

2. A radiator for automobiles including upper and lower tanks, side frames rigidly connected to said upper and lower tanks, a supporting plate connected to the upper face of the lower tank, a radiator core supported by said plate, said radiator core having rigid metal frames at the upper and lower ends thereof, and flexible strips connected to said rigid frames, said flexible strips being connected respectively to the upper and lower tanks, said upper flexible strips having elongated openings through which the securing bolts pass whereby said radiator core may be secured in place without tilting or straining the same.

3. A radiator for automobiles including upper and lower tanks, side frames rigidly connected to said tanks, a supporting plate connected to the upper face of the lower tank, a radiator core extending from the lower tank to the upper tank, rigid metal strips, and flexible metal strips secured to the lower end of said radiator core and forming a rigid frame therefor, said flexible metal strips being secured to the lower tank, rigid metal strips, and flexible strips connected to the upper end of said radiator core and forming a rigid frame therefor, said flexible strips being connected to the upper tank.

4. A radiator for automobiles including upper and lower tanks, side frames rigidly connected to said tanks, a supporting plate connected to the upper face of the lower

tank, a radiator core extending from the lower tank to the upper tank, rigid metal strips, and flexible metal strips secured to the lower end of said radiator core and forming a rigid frame therefor, said flexible metal strips being secured to the lower tank, rigid metal strips, and flexible strips connected to the upper end of said radiator core and forming a rigid frame therefor, said flexible strips being connected to the upper tank, said flexible strips at the upper end of the radiator core having elongated openings for the securing bolts which permit the radiator core to be secured without tilting or straining the same.

5. In an automobile radiator, the combination of a rigid frame including upper and lower tanks and a radiator core, a rigid metal strip secured to said core and supported on said lower tank, a flexible metal strip secured to said core and rigid strip, and means for connecting the free end of said flexible strip to said lower tank.

6. In an automobile radiator, the combination of a rigid frame including upper and lower tanks and a radiator core, means forming a rigid frame at the lower portion of said core, a flexible metal strip secured thereto, and means connecting said strip to said lower tank.

In testimony whereof, I affix my signature, in the presence of two witnesses.

EDWARD H. ELLISON.
